UNITED STATES PATENT OFFICE.

CHARLES W. KIRSCH, OF STURGIS, MICHIGAN, ASSIGNOR TO KIRSCH MANUFACTURING CO., OF STURGIS, MICHIGAN, A CORPORATION OF MICHIGAN.

CURTAIN-ROD.

1,245,354.

Specification of Letters Patent.

Patented Nov. 6, 1917.

Application filed July 24, 1916. Serial No. 111,008.

To all whom it may concern:

Be it known that I, CHARLES W. KIRSCH, citizen of the United States, residing at Sturgis, in the county of St. Joseph and 5 State of Michigan, have invented certain new and useful Improvements in Curtain-Rods; and I do hereby declare the following to be a full, clear, and exact description of the invention, such as will enable others 10 skilled in the art to which it appertains to make and use the same.

My invention relates to curtain rods and more particularly to means for interlocking telescopedically interfitting members of curtain rods against relative longitudinal movement. The main object of the invention is to provide simple and efficient interengaging formations on the telescopedically interfitting parts of curtain rods whereby to 20 render them inseparable and incapable of relative longitudinal movement.

A further object of the invention is to provide a channel-shaped curtain rod built up of two or more telescopedically interfitting 25 members adjusted to provide rods of desired lengths, the members whereof are engaged with each other in such a manner that the parts are held against relative longitudinal movement.

30 My invention relates more particularly to curtain rods consisting of a plurality of telescopedically interfitting members having longitudinally extending edge flanges, and consists essentially in deforming the said 35 edges laterally of their length to provide interengaging formations on said members which will efficiently prevent the slightest relative longitudinal movement thereof.

My invention will be more readily understood by reference to the accompanying 40 drawings forming part of this specification, and in which I have illustrated a sectional telescopic curtain rod having the several parts locked against relative longitudinal 45 movement in accordance with my invention.

In said drawings:

Figure 1— is a perspective view of a sectional tubular curtain rod having parts adapted to be held together by indentations 50 formed in accordance with my invention.

Fig. 2— is a fragmentary rear elevation of the rod illustrating the means by which I hold the several parts of the rod against relative longitudinal movement.

Fig. 3— is a fragmentary horizontal section on the line 3—3 of Fig. 2.

Fig. 4— is a vertical section on the line 4—4 of Fig. 2.

The rods to which my invention particularly applies consist of flat strips of metal 60 having overturned or channeled edge-flanges opposing each other which telescopically interfit and border a relatively wide longitudinal slot through which a tool may be inserted to engage and crimp the edge 65 portions of the flanges.

In the form shown the rod comprises end members A, and a middle member B. These members are channel-shaped in cross-section, as shown in Fig. 4—, having inturned 70 longitudinal flanges C and D respectively, the end members being adapted to telescopically receive the ends of the middle member within the same. The inner opposed edges of the flanges C and D border a longitudinal 75 slot in each member, and the inner edges of the telescopically interfitting members are, as shown, substantially coincident.

The two end members A and the middle member B are adapted to be relatively longitudinal 80 adjusted to produce a curtain rod to correspond with and fit upon the fixed rod supports F mounted on a window-casing, or the like, and when this has been accomplished I lock the telescopic members 85 together to hold them permanently in such adjusted positions.

To accomplish this interlocking of the tubular members I indent the overlapping edges thereof, as shown at G, by forcing the 90 outer edge D inwardly against the inner edge C and causing the inner edge to be likewise indented. I thereby form a projection H on one of the members and an indentation or recess J in the opposed surface 95 of the other member to receive said projection, or in other words, I provide a projection on one member and coöperating shoulders on the other member which prevent any relative longitudinal movement of the two 100 members. As the metal of which the rod parts are formed is quite thin, these indentations are very easily formed by means of a small screw-driver or any similar tool, without affecting the outer side of the curtain rod. As I prefer to make these indentations quite small I preferably make several of them on each edge of the slot at each 105

telescopic joint or connection in the curtain rod. The several parts of the rod are thus securely held against longitudinal movement relatively to each other, but, as the indentations are not deep the parts of the rod can be separated if desired, by applying sufficient force to pry the contacting or overlapping edges sufficiently to disengage the projections on the outer edge from the indentations on the inner edge.

10 I claim:

A curtain rod comprising telescopically interengaged hollow members having opposed overhanging edge-flanges, the flanges of the larger overlapping the flanges of the

smaller of said members and the flanges of both members bordering a longitudinal slot, and interlocking formations permanently securing said members against relative telescopic movement extending laterally inwardly from the edges of the overlapped flanges and constituting distortions of the same.

5 In testimony whereof I have signed my name in presence of two subscribing witnesses.

CHARLES W. KIRSCH.
